UNITED STATES PATENT OFFICE.

WILLIAM F. SMITH, OF ST. LOUIS, MISSOURI.

VENDING-MACHINE.

1,294,964.

Specification of Letters Patent. Patented Feb. 18, 1919.

Application filed March 21, 1918. Serial No. 223,768.

To all whom it may concern:

Be it known that I, WILLIAM F. SMITH, a citizen of the United States, residing at St. Louis and State of Missouri, have invented 5 a new and useful Vending-Machine, of which the following is a specification.

The device forming the subject matter of the present invention is a vending machine of the coin controlled variety, and relates 10 more particularly to a machine of this character which is designed to contain rolls of flexible material, such as paper, portions of which it is adapted to deliver when the mechanism is released by the insertion of a 15 suitable coin.

The device is designed, primarily, for the vending of accident insurance policies and the main object of the invention is the provision of means for presenting a portion of 20 the policy to be delivered that the purchaser's name may be inscribed thereon, together with such other information as may be desired, and also means for recording the name and other information when inscribed.

25 A further object of the invention is the provision of means for delivering one policy upon release of the operative mechanism.

The invention also contemplates the provision of means for easily detaching a policy 30 from the roll.

A still further object contemplated by the invention is the provision of a coin released locking mechanism and means for temporarily locking the delivery mechanism when 35 the coin released locking mechanism has been unlocked.

The invention also contemplates the provision of a delivery roller and means, released by the coin, for automatically locking 40 the roller after each revolution thereof.

The invention further contemplates the production of a simple, durable, and efficient vending machine.

With the foregoing and other objects in 45 view which will appear as the description proceeds, the invention resides in the combination and arrangement of parts and in the details of construction hereinafter described and claimed, it being understood 50 that changes in the precise embodiment of the invention herein disclosed can be made within the scope of what is claimed without departing from the spirit of the invention.

One practical embodiment of the inven-

tion is shown in the accompanying drawings, wherein:—

Figure 1 is a perspective view of a complete vending machine constructed in accordance with the invention;

Fig. 2 is a plan view of the same with the outer casing in section and parts removed;

Fig. 3 is a view in side elevation of the vending machine with the outer casing in section;

Fig. 4 is a similar view with portions removed and showing the parts in released positions;

Fig. 5 is a central longitudinal section;

Fig. 6 is a transverse section on the line 6—6 of Fig. 5;

Fig. 7 is a fragmentary view in elevation showing the gearing between the rollers;

Fig. 8 is a fragmentary detail showing the locking mechanism in side elevation;

Fig. 9 is a section on the line 9—9 of Fig. 8.

In carrying out the invention there is provided a base 10, herein shown as rectangular, which may be formed of wood or other convenient material. The operative 80 mechanism of the device is mounted in a supporting frame which is seated on the base 10 and which consists of vertically disposed side plates 11 which are connected at the forward and rear ends of their lower 85 edges by the horizontal cross bars 12. The plates 11 are also held at their forward and rear ends, and adjacent their upper edges, by the horizontal tie rods 13 and 14, respectively. This supporting frame is clamped 90 to the base 10 by means of retaining hooks 15 which are engaged over the cross bars 12 and secured to the base 10 by screws or otherwise.

A horizontally disposed shaft 16 extends 95 transversely of the main supporting frame, in the side plates 11 of which it is journaled, and the ends of this shaft protrude beyond the plates 11. On one protruding end of the shaft 16 is secured a crank arm 17 provided 100 with a handle 17'. On the same end of the shaft 16 and close to the outer face of the side plate 11 is secured a spur gear 16', while on the other protruding end of the shaft 16 a pinion 16'' is rigidly secured. 105

The spur gear 16' meshes with the inner member of a double pinion 18 which is rigid on one protruding end of the shaft or pintle

of a horizontally arranged, knurled roller 19, the shaft or pintles of which are journaled in the side plates 11 of the supporting frame of the device. The outer member of 5 the double pinion 18 meshes with a spur gear 20 which is rotatable on a stub shaft 21, secured to and extending outwardly from the side plate 11.

The pinion 16" meshes with a spur gear 10 22 which is rotatable on a stub shaft 23, secured to and extending outwardly from a side plate 11, and the spur gear 22 in turn meshes with a spur gear 24 rigid on the extending end of the shaft of a roller 25, 15 which roller is arranged transversely of the support at the forward end thereof and the shaft of which roller is journaled in the side plates 11.

A spur gear 26 is rigid on the protruding 20 end of the other pintle of the knurled roller 19 and this spur gear meshes with the spur gear 27 which is rigid on the protruding end of the pintle of another knurled roller 28, which roller is arranged transversely of 25 the support and parallel with and closely spaced from the roller 19.

From the foregoing it will be apparent 30 that, when the crank arm 17 is revolved clockwise, as viewed in Fig. 1, rotary motion counter clockwise will be imparted, through the spur gear 16' and inner portion of the pinion 18, to the knurled roller 19. At the same time rotation clockwise will be 35 imparted through the outer portion of the pinion 18 to the spur gear 20, for a purpose hereinafter to be set forth. Rotary motion will also be imparted through the spur gears 26 and 27 to the knurled roller 28, such motion being clockwise, or opposite to that 40 imparted to the roller 19.

At the same time, the pinion 16" which is 45 rotating counter clockwise imparts rotary motion to the spur gear 22, said motion being in a clockwise direction. The gear 22 in turn imparts, through the gear 24, rotary motion counter clockwise to the roller 25.

A table 29 extends transversely of the support, at the forward end thereof, and is secured to the side plates 11 adjacent their 50 upper edges. A strip 30 of paper or like recording material is led over the table 29 and has its forward end secured to the roller 25 upon which it is adapted to be wound as the roller 25 is rotated as just described. 55 The strip 30 is led from the rear edge of the table 29 beneath the shaft 16 and to a supply spool or reel 31 which is journaled in the strips 32, which strips are secured to the side plates 11 by screws or otherwise and are 60 formed of slightly resilient material so that they may be sprung to easily receive the spool and also grip the ends of the spool to prevent spinning thereof.

A strip of copying material 33', such as 65 carbon paper, extends across the table 29

and overlies the paper 30, and this strip is looped about the rod 13 and the shaft 16 to retain the strip in place upon the table.

The accident policies 33, or other articles to be delivered, are arranged in a roll on a 70 spool or reel 34 which is journaled in the resilient supporting strips 35 which are secured to the side plates 11 by screws or otherwise. The strip of policies 33 is led from the spool 34 between the knurled rollers 19 75 and 28 and across the table 29, overlying the copying material 33' so that should one write upon that portion of the policy which rests upon the table an impression of such writing would be recorded on the strip 30 and be re- 80 tained within the machine and upon the spool 25.

Having thus seen the operative connection between the various parts and the purpose thereof, we will now consider the mechanism by which the parts are locked and the method of releasing such mechanism. 85

A substantially triangular plate 35' is secured to one side plate 11 from which it is suitably spaced, and with which it defines 90 a coin chute and plunger housing. A suitable inlet port or hopper 36 may be provided leading to the chute, and a plunger 37 is slidable between the plate 35' and the side plate 11, the plunger being provided with a laterally extending pin 38 which projects through and slides in a slot 39 in the plate 35'. A resilient element, such as the spring 40 which is secured to the side of the plate 35' and one branch of which contacts 95 the extending end of the pin 38, is provided for retaining the plunger in its normal or raised position.

A discharge slot 41 is provided at the lowermost vertex of the triangular plate 35' 105 and the plunger 37 terminates short of this slot, when in normal position, a sufficient distance to allow a coin of the required size to enter between the end of the plunger and the slot. Extending through an aperture 42 formed in the side plate 11 and positioned before the slot 41 is a laterally extending lug 43 which is formed on a latch bar 44. The latch bar 44 is horizontally arranged and mounted to slide back and forth on the outer face of the side plate 11, being held to slide upon the plate by screws 45 or other like securing elements which extend through 110 slots formed longitudinally of the bar. The rear end of the bar 44 is turned outwardly and apertured to provide an attachment for one end of a retractile spring 46 the other end of which is suitably secured to the side plate 11.

The forward end of the latch bar 44 is reduced and at this end is provided a finger 47 which is pivotally secured to the outer face of the bar 44 and which is drawn toward a position beside the reduced end by means of a spring 48, or like resilient ele- 125 130

ment. This forward reduced end of the latch bar 44 abuts the periphery of a cam disk 49 which is carried on the stub shaft 21 and which rotates with the spur gear 20. The cam disk 49 is formed at one point on its periphery with a normally downwardly facing shoulder 50 which is adapted to contact with and overlie the reduced end of the latch bar 44 when the parts are in normal or locked position. A cam strip 51 is affixed to the outer face of the cam disk 49 and at the periphery of the disk and this strip, when the cam disk is in normal position, extends below the shoulder 50 and presents a shoulder to contact and overlie the end of the finger 47. It will thus be seen, as indicated most clearly in Figs. 8 and 9, that when the cam disk 49 is in normal position the finger 47 is depressed against the force of the spring 48.

From the foregoing it will be seen that when a proper coin or disk 52, see Fig. 5, is deposited in the hopper 36 it will gravitate through the chute to a position of rest between the lower end of the plunger 37 and the laterally projecting lug 43 of the latch bar 44 so that, when the plunger 37 is forced downwardly, the coin or disk 52 is projected through the slot 41 to force the lug 43 and latch bar 44 rearwardly against the force of the retractile spring 46. This will draw the reduced forward end of the latch bar 44 from beneath the shoulder 50 and, at the same time, draw the finger 47 from beneath the end of the cam strip 51. When the finger 47 is released from the cam strip 51 it will rock upon its pivot under the force of the spring 48 to a position beside the reduced end of the bar 44 and in this position its free end will abut the periphery of the cam strip 51 thereby holding the end of the latch bar 44 removed from beneath the shoulder 50 and in position to engage with the periphery of the cam disk 49 when the disk is revolved. As will be readily understood, this serves to unlock the cam disk and permit the same to make one revolution.

As will be seen most clearly in Fig. 3, the lug 43 also projects through the aperture 42 and extends slightly beyond the outer face of the bar 44, and this extending end of the lug is adapted to strike the upper end of an arm 53 when the latch bar 44 is retracted. The arm 53 is pivotally secured, at its lower end, to the outer face of a side plate 11. A latch arm 54 is also pivotally secured at its lower end to the outer face of the side plate 11 and a connecting link 55 joins the arm 53 to the latch arm 54, having an end pivotally secured to each. A retractile spring 56 has one end secured to the link 55 and the other end secured to the side plate 11 and serves to retain the arm 53 and latch arm 54 in their forward position for a purpose soon to be described.

A vertically disposed bar 57 is mounted to slide vertically on the outer face of the side plate 11 by means of a screw 58 or like securing element which passes through a slot formed in the bar 57. The bar 57 is adapted to extend above the upper edge of the side plate 11 when the bar is in its uppermost position. The lower end of the bar 57 is angularly disposed rearwardly and merges into an angled end 59 which is adapted to enter between the teeth of the gear wheel 16' when the bar is in its raised position and lock the wheel against rotation. The angled end 59 is preferably apertured to receive the forward end of a spring 60 which is secured to the outer face of the side plate 11 and which tends to retain the bar 57 in its uppermost position. A pawl 61 is pivotally secured by a screw 62 or other means which passes through a longitudinal slot formed in the bar 57 to the outer face of the side plate 11 and this pawl is adapted to engage the teeth of the gear wheel 16' and lock the wheel against motion in one direction.

The journals of the knurled roller 28 extend through slots 63 formed in the side plates of the supporting frame and are contacted by resilient elements 64 to press the roller downwardly and yieldingly hold the same against the roller 19.

The mechanism thus far described is housed in a suitable outer casing 65 the lower edge of the front plate of which is turned inwardly to form a flange 66 which is adapted to take under the forward end of the supporting frame and which is notched to take about the clamping hooks 15. At its rear end this outer casing is provided with a transverse bar 67 which is engaged by a clamping plate 68 which plate is held in place by a wing nut 69 threaded on a stud 70 which is secured to and rises from the base plate or block 10.

The casing 65 is provided in its rear plate with a door 71 through which access may be had to the interior of the casing for the purpose of releasing the casing to remove the same, and for other purposes. A window or transparent panel 72 is provided in the upper plate of the casing 65 through which the interior of the structure may be observed. Slots are also provided in the top plate of this casing to permit the passage therethrough of the plunger 37 and the alinement of the hopper with one of said slots.

The top of the casing 65 is provided, adjacent its forward end, with an opening which overlies the table 29 and which is closed by a door 73 hinged at 74. The door 73 is adapted to be swung open, when unlatched, by any suitable resilient means; as herein shown the door is formed with an extending lug 75 which projects rearwardly of the hinge 74 and which is engaged by

one end of a retractile spring 76 the other end of which is made fast to the outer face of the side plate 11. An angular catch 77 is secured to the under face of the door 73 and is positioned to be engaged by the latch 54 when the door is in closed position.

In practice the device operates in the following manner:—

The door 71 is unlocked and opened and 10 the wing nut 69 unscrewed to loosen the clamping plate 68 and permit the outer casing 65 to be removed. A spool or reel 31 containing the web or paper 30 may then be put in place and the paper 30 threaded 15 over the table 29 and attached to the roller 25. The carbon paper 33' is then secured in place over the table and paper 30; the reel of printed policy blanks 34 inserted and the blanks 33 led between the rollers 19 and 20 28 and over the table 29. The outer casing is then replaced and clamped down and the door locked.

To secure a policy, a coin is inserted in the hopper 36 and the plunger 37 depressed, 25 as heretofore described, causing a rearward movement of the latch bar 44 and expulsion of the coin through the slot 41 into the interior of the device. When the latch bar 44 moves rearwardly, the cam disk 49 is unlocked as 30 heretofore described and the arm 53 is rocked rearwardly drawing with it the latch arm 54 and releasing the catch 77, whereupon the door 73 flies open under the force of the spring 76. When the door 73 opens 35 the bar 57, the upper end of which normally contacts the door and which bar is normally depressed by the door, is free to move upwardly under the force of the spring 60. Upon the upward movement of the bar 57 40 the angled lower end 59 will be brought between teeth of the gear wheel 16' and lock the wheel against rotation.

The customer may now write his name, address, and such other information as may 45 be required upon that portion of the policy overlying the table 29 and the carbon paper 33' will cause such writing to be recorded upon the strip of paper 30.

After writing the information required 50 upon the policy, the customer closes the door 73, thereby depressing the bar 57 and withdrawing the end 59 from between teeth of the wheel 16' thus unlocking the wheel for rotation. The cam disk is also unlocked 55 as heretofore set forth and the crank 17 may

be given a complete revolution, thereby giving the knurled rollers a complete revolution, which draws the web 33 forwardly the length of one policy. Upon this revolution the various other rollers rotate as heretofore set forth.

Having thus described the invention, what is claimed as new and sought by Letters Patent, is:—

1. A vending machine, including a casing 65 provided with an opening, a door normally closing the opening, a latch for holding the door in normally closed position, an arm pivotally mounted within the casing, an element connecting the latch and arm, delivery 70 mechanism within the casing, locking means for the delivery mechanism engaged by the door and normally held in unlocked position thereby, a latch bar within the casing to normally lock the delivery mechanism, said 75 bar engageable with the arm to rock the same about its pivot and actuate the latching arm to release the door, and coin controlled means for moving the latch bar from normal position.

2. A vending machine, including a casing for containing documents to be delivered, said casing having an opening, a door normally closing the opening and to be opened for inscription of a document, delivery mechanism within the casing for delivering documents, said mechanism including a disk 85 formed with a shoulder on its periphery; and a cam strip on the disk and formed with a shoulder spaced circumferentially 90 from the shoulder of the disk, an element engaging the shoulder of the disk to normally lock the delivery mechanism against operation, an element carried by said first 95 element and normally engaging the shoulder of the cam strip operating when the first element is released from the shoulder of the disk to retain said element in released position, coin controlled means for unlatching the door and releasing the elements to unlock the delivery mechanism, and means for restoring the elements to normal position.

In testimony that I claim the foregoing as my own, I have hereto affixed my signature in the presence of two witnesses.

WILLIAM F. SMITH.
